UNITED STATES PATENT OFFICE.

WATTS COOKE AND DANIEL CARLOUGH, OF PATERSON, NEW JERSEY.

MACHINE FOR UPSETTING EYE-BARS.

SPECIFICATION forming part of Letters Patent No. 390,458, dated October 2, 1888.

Application filed November 3, 1887. Serial No. 254,194. (No model.)

To all whom it may concern.

Be it known that we, WATTS COOKE and DANIEL CARLOUGH, both of Paterson, Passaic county, in the State of New Jersey, have invented a certain new and useful Improvement 5 in Machines for Upsetting Eye-Bars, of which the following is a specification.

It is common to make eye-bars to serve as ties in roofs, bridges, &c., by rolling the bar of 10 uniform section throughout and afterward thickening each end by the process known as "upsetting." We have in patents to us dated October 13, 1885, No. 328,290, and July 13, 1886, No. 345,573, set forth mechanism intended 15 for this purpose.

Our present invention is an important improvement in the same general direction. We provide exchangeable cheeks, which allow the 20 same bed and the same upper and lower dies to serve for upsetting bars having a considerable variation in the width and thickness. One pair of removable cheeks is applied at the 25 neck, the junction of the eye with the main body, and serve to shape that important portion of the bar. By exchanging these cheeks for others of greater or less width we adapt the 30 machine for treating bars of different widths. The space at each side for the eye to widen need not be varied. A sufficient width of 35 space may be allowed for the widest eye. When in treating a smaller bar there is not sufficient metal to fill the space, no mischief results. The subsequent treatment in the 40 shaping-dies corrects all irregularities in the form. We employ a pair of removable cheeks at the other end of the eye farthest from the neck. These, like the cheeks at the neck, are 45 exchangeable, and will allow a similar range in the widths of the bars being treated. The function of these end cheeks is peculiar. They apply each side of the hot bar and support that portion adjacent to the end as it is driven forward by the header. In other words, instead of leaving the entire length of the iron which is to be upset without lateral support during 50 the whole upsetting period, our present invention supports a considerable portion of the metal which is to be upset by these end cheeks.

There is in our present invention a portion 55 of the metal left unsupported laterally; but it is only such portion of the length as the eye is

to finally maintain when the upsetting is completed—that is to say, if twelve inches of metal is to be upset, so as to form an eye only six inches long, our former plan would have left 55 the whole twelve inches without lateral support during the entire upsetting operation. Our present invention, on the contrary, leaves only six inches—the six immediately adjacent to the neck—thus laterally unsupported, and 60 supports the six inches nearest the extreme end of the bar. When in the act of upsetting the header moves strongly inward and upsets the metal, the stock at the end of the bar and adjacent thereto is effectually supported laterally. 65 It has no other course than to move endwise under the strong force impressed by the header. The portion which is unsupported near the neck is allowed to spread, and as more and more of the portion which originally lay between 70 the end cheeks is by the upsetting movement forced into the space which is to form the eye and becomes liberated this portion of the metal is successively spread until the whole eye is shaped.

Our experiments indicate that the metal is less likely to buckle or double sidewise because of its being thus supported laterally near the end during the early portion of the upsetting operation.

The accompanying drawings form a part of this specification and represent what we consider the best means of carrying out the invention.

Figure 1 is a side elevation. Fig. 2 is a central longitudinal vertical section. Fig. 3 is a plan view with the top casting and the accompanying slide which serves as the upper die removed. Fig. 4 is a section on the line $x-x$, looking in the direction of the arrows in Figs. 85 1, 2, and 3. Fig. 5 is a section on the line $y-y$ in the same figures, looking in the same direction.

Similar letters of reference indicate corresponding parts in all the figures where they 95 occur.

A is a bed-casting, certain portions of which will be designated when necessary by additional marks, as A' A''. The bottom die is a slide, B, which is capable of traversing end- 90 wise in the casting A, and is formed with a strong upright, B', which we will term the

"header." Its function is to act forcibly against the end of the heated bar and upset it. At the end of the bottom die, opposite the header, is an extension or tongue, B^2 , which, as the up- 5 setting progresses, moves between elevated portions A' of the bed and forms a support for the under portion of the bar adjacent to the neck. The bed is provided with stout up- rights $A^2 A^3$, which take hold of the main top 10 casting, D , and allow it to only move up and down. This top casting, D , is moved vertically by a plunger, E , of a hydraulic press mounted above. (Not represented.)

G is a slide, which serves as the upper die. 15 It is capable of moving endwise during the upsetting operation, being connected to the top casting by a longitudinal rib, G' , of dovetail section, formed on its upper face and engaged in a corresponding groove, d , planed or 20 otherwise produced in the base of D .

$C C$ are the neck-cheeks. Each is provided with an offset, C' , which engages in a transverse groove, a , in the portion A' of the bed. When the top casting, D , and the upper die, G , are 25 raised, these cheeks $C C' C C'$ may be easily taken out and others may be introduced, thus readily adapting the machine to treat wider or narrower bars.

$K K$ are the end cheeks, adapted to apply 30 against the edges of that portion of the bar which is to be driven inward upon the other parts to form the eye. These end cheeks, like the neck-cheeks C , may be removed and exchanged, substituting wider or narrower, 35 longer or shorter, end cheeks, according to the width of the iron being treated and the length of the eye which is to be finally produced. One end of each end cheek, K , is properly formed to shape the adjacent portion of the 40 eye. The other end reaches outward, as indicated by K' , and forward, as indicated by K^2 . There is also a corresponding arm, which reaches outward from K , as indicated by K^3 , and rearward, as indicated by K^4 . These arms 45 take hold loosely of the stout projection A^3 and keep the cheek in the required position. They hold the cheek against being displaced either endwise or inward by any force.

The operation of all the parts will now be 50 understood. The hot bar M may be introduced by an endwise thrust while the top casting, D , and the attached upper slide, G , are being depressed. When the bar M has abutted against the header B' , and the top slide, G , is firmly pressed down into position, the 55 ram R , driven by a steam-piston, (not represented,) moves endwise against the header B' and commences to upset the bar M . In this operation a considerable length of the heated 60 bar is supported laterally by the end cheeks, $K K$. The upsetting all takes place a little farther down. The length of the bar, which is unsupported laterally at this point, is so small that the bar is certain to thicken properly without buckling to either side. As the 65 upsetting operation proceeds and more and more of the hot metal is thrust from between

the end cheeks, $K K$, into the free space it is successively spread laterally, and when the header stops, which is with its front edge 70 flush with the working ends of the end cheeks, $K K$, all the metal at the end of the bar is properly compressed into the eye, and all the parts are allowed to return to their original positions. The eye-bar is removed by lifting 75 it out, and the machine is ready to treat a fresh bar.

Modifications may be made in the details without departing from the principle or sacrificing the advantages of the invention. We 80 can vary the form of the working ends of the neck-cheeks $C C$, and also of the end cheeks, $K K$, so as to give the eye an octagonal form instead of the approximately circular one indicated. The working face of the header B' 85 may be concave to correspond to the regular contour of the eye. There may be any ordinary or suitable means to hold the main body of the bar M during the upsetting operation.

We propose to provide a stock of neck- 90 cheeks $C C$ and end cheeks, $K K$, of different widths to treat different widths of bars. We may also provide these cheeks of different thicknesses to better treat bars of corresponding thickness. There is less necessity 95 for this, however, because the metal will always be sufficiently guided by cheeks which are thin enough to adapt them for the thinnest bars which are likely to be treated. When thicker ones are treated they may project above 100 the upper surfaces of the cheeks. No mischief will result from a considerable difference in thickness.

The proper motions of the several parts may be induced by other means than those indicated. It is not essential that there be a steam-piston to operate the ram R and drive the header, or a hydraulic press to operate the top casting, A' . It is sufficient that the ram R move horizontally at the proper time with 110 sufficient force, and that the top casting, D , be held downward with sufficient force to restrain the thickening of the bar and compel the upsetting action to dislodge it laterally, and that it have a capacity to subsequently raise 115 the parts to allow the removal of the eye-bar with its nearly-completed eye.

It will be understood that the eye is subsequently treated at the same heat by shaping with pressure in a die of suitable form and 120 punching or otherwise producing an accurately-formed hole for the transverse pin.

We claim as our invention—

1. In a machine for upsetting eye-bars, the end cheeks, $K K$, and header B' , arranged as 125 shown, to allow the hot bar to be received and guided during the upsetting operation, as herein specified.

2. In a machine for upsetting eye-bars, in combination with the base A , having the up- 130 rights A^3 , the removable cheeks K , each hav- ing arms $K' K^2$ and $K^3 K^4$, embracing said up- rights, as and for the purpose specified.

3. The bed A , with elevations A' and up-

rights A² A³, in combination with the top casting, D, and means, E, for operating it vertically, and with top die, G, bottom die, B, header B', and tongue B'', and with the four exchangeable 5 cheeks C C and K K, all arranged for joint operation, as herein specified.

In testimony whereof we have hereunto set our hands at Paterson, New Jersey, this 29th

day of October, 1887, in the presence of two subscribing witnesses.

WATTS COOKE.
DANIEL CARLOUGH.
